VALVE

Paulsen Spence, East Orange, N. J.

Application June 18, 1931, Serial No. 545,225

5 Claims. (Cl. 137—153)

My invention relates to a valve and more especially to an automatic valve which is operated by a diaphragm which is exposed to the pressure of an expansible fluid contained in a closed container. This application is a continuation in part of my co-pending application Serial No. 366,838, filed May 29, 1929.

In valve construction, it is sometimes desirable that a valve or valve stem should be moved by means of two or more springs which act in parallel on a spring yoke attached to the valve stem. The common practice has been to attach the spring yoke rigidly to the valve stem. When this is done, inequality in the tension of the springs or any sticking of one of the springs will tend to tilt the yoke and valve stem, thereby causing the valve stem to bind in the stuffing-box or other guide means. Any lack of alignment of the various guide means for the valve stem will also cause binding of the valve stem. When the valve is an automatic valve operated by a sensitive diaphragm, any binding of the valve stem will render the valve inoperative. It is also common practice to have the diaphragm coact with a disk which is rigidly connected to the valve stem or yoke. When this is done, any tilting of the valve stem or yoke will tilt the disk, and when the disk is tilted, it may injure the diaphragm.

When the valve is operated by a diaphragm which is exposed to the pressure of an expansible fluid contained in a closed container, the diaphragm is usually made separate from the remainder of the container and is subsequently attached thereto by means which will permit of the removal and replacement of the diaphragm when necessary. Since the expansion of the fluid contained in the closed container is relied upon to operate the valve, it is important that there shall be no leakage between the diaphragm and the remainder of the container, and special obturation means must be employed.

It is an object of my invention to provide a valve in which binding of the valve stem due to lack of alignment of the guide means for the valve stem is eliminated by making the valve stem in two or more parts.

It is a further object of my invention to provide a diaphragm-operated valve in which binding of the valve stem due to inequality in the tension of the springs is eliminated by the insertion of a non-rigid coupling between the spring yoke and the valve stem.

It is a further object of my invention to provide a diaphragm-operated valve in which injury to the diaphragm due to tilting of the disk which

coacts with the diaphragm is eliminated by making the disk as a separate member and by providing means for holding the disk and yoke substantially in alignment while yet allowing for some play between them.

It is a further object of my invention to provide a valve which is operated by a removable and substantially flat diaphragm which is exposed to the pressure of an expansible fluid contained in a closed container, and in which there is complete obturation between the diaphragm and the remainder of the container.

Other objects and advantages will be apparent as the specification proceeds.

In the drawing which shows, for illustrative purposes only, preferred forms of the invention—

Fig. 1 is a sectional view of a valve illustrating features of the invention;

Fig. 2 is a similar view of a modification.

In said illustrative drawing, 1 represents a valve body having chambers 2 and 3 therein. 4 represents a valve head for controlling the passage of fluid between the chambers 2 and 3. 5 is a hood secured to the body 1. This hood has a bore therethrough and a stuffing-box 6 at one end of the bore. 7 is a packing which is compressed in the stuffing-box by means of the gland 8 and gland nut 9. A diaphragm casing is provided, having an upper part 10 and a lower part 10^a. The casing is secured to the hood 5 by means of the bolts 11—11. 12—12 are spiral springs surrounding the bolts 11—11 and carried by the followers 13—13 which are carried by the adjusting nuts 14—14 which are threaded on the bolts 11—11. 15 is a yoke which is carried by the springs 12—12. 16 is a disk which is carried by the yoke 15 and which coacts with a removable and substantially flat diaphragm 17. The diaphragm 17 is gripped adjacent to its perimeter between opposed annular bearing surfaces on the parts 10 and 10^a, and these parts are urged toward each other by removable means, such as the circularly arranged bolts 17^a. The diaphragm 17 and the part 10 together form a diaphragm chamber 17^b.

The valve stem may be made in two or more parts. In the drawing, I show a valve stem 18 secured to the head 4 and extending into the bore of the hood 5, and a second valve stem 19 connected to the yoke 15 and extending through the stuffing-box 6 and into the bore of the hood and coacting with the end of the valve stem 18. By making the valve stem in two parts, I eliminate any binding of the valve stem which would otherwise be caused if the bore of the gland 8 were not

accurately aligned with the bore in the hood 5. When the valve stem is made in two parts, the stuffing-box friction is overcome by the springs 12-12 and the valve head 4 is raised by the pressure of the fluid in the chamber 2.

I also provide means for holding the disk 16 and the yoke 15 substantially in alignment while yet allowing for some play between them. In the form shown in the drawing I provide an aligning pin 20 which fits loosely into bores in the upper surface of the yoke and in the lower surface of the disk. By this construction I eliminate danger of damage to the diaphragm 17 by the tilting of the disk 16 which might occur if the disk and yoke 15 were rigidly connected together and the yoke should be tilted by some inequality in the tension of the springs 12-12.

In the modification shown in Fig. 2 I show a non-rigid coupling between the yoke 15 and the valve stem 19. In the particular form shown, a coupling member 21 is secured to the upper end of the valve stem 19. The upper end of the coupling member 21 is flanged, and the flanged portion is loosely held in a flanged recess in the bottom of the yoke 15. The coupling member 21 could, of course, be made integral with the valve stem 19. By means of this coupling I eliminate the danger of binding of the valve stem due to inequality in the tension of the springs 12-12.

The valves shown can be used as thermostatic valves as shown in Fig. 2. 22 is a thermostat bulb, and 23 is a pipe connecting the interiors of the bulb 22 and of the diaphragm chamber 17^b. The bulb 22, the pipe 23, and the chamber 17^b together form a closed container in which is placed a quantity of a fluid which expands as its temperature is increased.

In Fig. 2 I show means for obtaining complete obturation between the diaphragm 17 and the upper part 10 of the diaphragm casing. On the lower part 10^a of the diaphragm casing there is formed an annular upwardly projecting flange 24. This flange is narrow and its top surface is rounded on a radius of the order of one-sixteenth of an inch. 25 is an annular gasket which is preferably made of lead or other soft metal. When the bolts 17^a are tightened, the flange 24 will compress the diaphragm 17 against the gasket 25 so as to effect complete obturation.

By means of the adjusting nuts 14-14, the tension of the springs 12-12 can be adjusted so that the valve will close when the fluid in the diaphragm chamber 17^b reaches a predetermined pressure, or when the temperature to which the thermostat bulb 22 is exposed reaches a predetermined limit.

While the invention has been described in considerable detail and illustrative forms have been shown, I do not wish to be strictly limited to the forms herein shown, since changes may be made within the scope of the invention as defined in the appended claims.

I claim:

1. A diaphragm-operated valve comprising a body having two chambers therein, a valve head,

a hood secured to said body, said hood having a bore therethrough, a valve stem guided within said bore, a plurality of springs supported by said hood, a yoke supported by said springs, diaphragm means for moving said yoke, and means for loosely coupling said yoke and said stem, said yoke and said springs being located intermediate said hood and said diaphragm, said springs, yoke and diaphragm means being bodily carried by said hood and removable as a unit therewith.

2. A diaphragm-operated valve comprising a body having two chambers therein, a valve head, an opening in said body to permit removal of said valve head, a hood secured to said body and closing said opening, said hood having a bore therethrough, a valve stem guided within said bore, a plurality of springs supported by said hood, a yoke supported by said springs, and diaphragm means for moving said yoke, said valve stem being loosely connected to said yoke, said springs, yoke and diaphragm means being bodily carried by said hood and removable as a unit therewith.

3. A diaphragm-operated valve comprising a body having two chambers therein, a valve head, a hood secured to said body, a diaphragm casing supported by said hood, a diaphragm within said casing, a disk coacting with said diaphragm, a yoke coacting with said disk, a plurality of springs interposed between said yoke and said hood and mounted eccentrically of said diaphragm, means for holding said disk and said yoke substantially in alignment while yet allowing for some play between them, and means for transmitting the motion of said yoke to said valve head, said diaphragm casing, disk, yoke and springs being bodily carried by and removable as a unit with said hood.

4. A diaphragm-operated valve comprising a body having two chambers therein, a valve head, a hood secured to said body, a plurality of springs carried by said hood, a yoke carried by said springs, a disk carried by said yoke, a diaphragm casing carried by said hood, a diaphragm within said casing and coacting with said disk, an aligning pin fitting loosely into bores in said yoke and said disk, and means for transmitting the motion of said yoke to said valve head.

5. A diaphragm-operated valve comprising a valve body, a hood removably carried thereby and having a through passage therein, a valve head for said valve body and having a stem guided in said through passage, a plurality of guide rods carried by said hood, a diaphragm casing fixedly carried by said guide rods, springs carried by said guide rods and interposed between said hood and said diaphragm casing, a diaphragm in said casing, a second valve stem to coact with said first mentioned valve stem and guided in said passage and coacting with said diaphragm, whereby movement of said diaphragm may move said valve head, and means for causing said springs to urge said diaphragm in one direction.
